(57) CLAIM

I claim the ornamental design for a covered casserole, as shown and described.

DESCRIPTION

FIG. 1 is a perspective view of a covered casserole according to the new design;

FIG. 2 is a right side view of the covered casserole shown in FIG. 1, the left side being a mirror image thereof;

FIG. 3 is a top view of the covered casserole shown in FIG. 1;

FIG. 4 is a front view of the covered casserole shown in FIG. 1;

FIG. 5 is a rear view of the covered casserole shown in FIG. 1; and,

FIG. 6 is a bottom view of the covered casserole shown in FIG. 1.

Features shown in broken lines in the drawings are not part of the claim.
